UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

TENSION MECHANISM FOR WINDING-MACHINES.

1,254,049.

Specification of Letters Patent. Patented Jan. 22, 1918.

Application filed October 9, 1916. Serial No. 124,439.

To all whom it may concern:

Be it known that I, JOHN O. MCKEAN, a citizen of the United States, residing at Westfield, in the county of Hampden and State of Massachusetts, have invented new and useful Improvements in Tension Mechanism for Winding-Machines, of which the following is a specification.

My invention is designed for application to the tension mechanism of winding machines in which the well known sewing machine tension, comprising two opposed disks, mounted for rotation upon an arbor, is employed.

15 In the drawings:—

Figure 1 is an end elevation of a tension device embodying my invention;

Fig. 2 is a front elevation of Fig. 1, looking in the direction of the arrow; and

20 Fig. 3 is a detail, partly in section, of the tension disks and the arbor on which they are mounted.

In this tension the principal object is to apply merely such a retarding influence as 25 will prevent the thread, after it has passed the disks and between the disks and the cop or bobbin being wound, from having slack. In a sewing machine the passage of thread through the tension disks is intermittent 30 and relatively slow. In a winding machine the thread travels constantly and at high speed between the disks.

Under normal conditions the thread passing from the delivery bobbin upward, 35 through the tension device A, B, to the spool or cop being wound is not retarded by the delivery bobbin, the thread being drawn off over the point of the delivery bobbin, which stands vertically beneath the tension device, 40 and the thread, as it enters between the disks A, B, is slightly diverted from its course by the rotation of the disks, which are slightly separated upon that side through which the thread passes, against the pressure of a light 45 spiral spring, S. Disk A is formed with a hub a, a', part a' being squared or of other angular cross section, and disk B is mounted upon the angular portion a', having a suitably shaped aperture, so that disk B must 50 rotate with the hub, but may have longitudinal movement thereon. The hub a, a' is mounted upon an arbor C secured in the outer end of a fixed rod C'. A presser member, b, is also mounted upon the arbor, one 55 end embracing the hub a' and impinging

upon the disk B, and washer b' is interposed between the other end of the presser member and the spring S, the spring S abutting at its other end against a washer d' and nut D mounted upon a threaded tube surrounding 60 the rod C'.

As the thread is drawn through the disks, the disks are rotated by the friction of the thread against their opposed faces, and the speed of rotation is normally controlled by 65 the balance established between the frictional urge of the thread upon the face of the disks and the frictional effect of the presser member, b, upon the back of disk B. The rotation is designed to be relatively 70 slow, owing to the fact that it is impractical to lubricate the bearing surface of the hub a, a' upon the arbor C owing to the proximity of the thread. Normally the desired effect is produced, but, due to imperfections 75 in winding of the delivery bobbin there are frequent and innumerable checks in the delivery, the immediate effect of which is to increase the draft between the delivery and the winding cop, tending to straighten out 80 the thread. The result is that the thread is drawn relatively hard against the hub of the tension disk and the slight resistance of the presser member b would be overcome 85 and the disks spun at a very high speed were it not that the slightest increase above normal of the draft upon the thread, while it pulls the thread against the hub also and at the same instant increases the upward lift on the detector lever E which is supported by 90 the thread and the pressure of the brake F against the hub, a, preventing racing of the disks and any possible winding of broken ends in the tension device. In actual operation the effects described above succeed one 95 another so rapidly that the brake increases and releases pressure on the hub with an extremely rapid series of actions and the disks under no circumstances are raced.

The detector lever E is pivoted at e upon 100 a bracket e' fast to the frame of the machine. That bracket also carries a stop e'' which limits the upward movement of the detector lever. I have shown the nut D as mounted upon a threaded sleeve C'' mounted upon 105 the rod C'. This threaded sleeve forms no part of my present invention, being useful only in connection with a shifting cam, arranged to permit the sleeve to be shifted as the cop grows to release tension on the spiral 110

spring S to keep the pressure on the disk B uniform. This latter invention is shown and described in my pending application Serial No. 75,802, and will form the subject of another application.

I claim:

In a tension device, a pair of disks mounted upon a hub for rotation; that hub;

a brake member mounted adjacent to the hub and in operation sustained by the thread 10 in close relation to the hub and pressed against the hub when the draft upon the thread is super-normal.

Signed by me at Boston, Mass., this 6th day of October, 1916.

JOHN O. McKEAN.
